UNITED STATES PATENT OFFICE

121,045

DESIGN FOR AN APPAREL RACK OR THE LIKE

Bernard M. Flannery, Galion, Ohio

Application April 23, 1940, Serial No. 91,893

Term of patent 14 years

all whom it may concern:
Be it known that I, Bernard M. Flannery, a citizen of the United States, residing at Galion, Crawford County of Ohio, have invented a new, original, and ornamental Design for an Apparel Rack or the like, of which the specification is a specification, reference being had to the accompanying drawing, forming part hereof.

I claim:

The ornamental design for an apparel rack or the like, as shown.
